(21) Appl. No.: **29/243,288**

(57) **CLAIM**

(22) Filed: **Nov. 22, 2005**

I claim the ornamental design of an industrial ink-jet press for screen printing, as shown and described.

(30) **Foreign Application Priority Data**

DESCRIPTION

May 30, 2005 (EP) 346804-0001

FIG. 1 is a right perspective view of an industrial ink-jet press for screen printing showing my new design;

(51) **LOC (8) Cl.** **18-02**

FIG. 2 is a front left perspective view thereof;

(52) **U.S. Cl.** **D18/53; 101/127.1**

FIG. 3 is a front elevation view thereof;

(58) **Field of Classification Search** D18/36-39,

FIG. 4 is a left elevation view thereof;

D18/56, 53-55, 99, 19, 50; 101/2, 5, 22,
101/23, 33, 41, 214, 364-366, 118, 127.1;
D8/71; D10/64; D6/407, 626; 234/25; 118/44;
38/36

FIG. 5 is a right elevation view thereof;

See application file for complete search history.

FIG. 6 is a rear elevation view thereof; and,

(56) **References Cited**

FIG. 7 is a top plan view thereof.
